UNITED STATES PATENT OFFICE.

HARRY F. HITNER, OF CREIGHTON, PENNSYLVANIA, AND TRAVIS E. OAKES, OF MOUNT VERNON, OHIO, ASSIGNORS TO PITTSBURGH PLATE GLASS COMPANY, A CORPORATION OF PENNSYLVANIA.

DEVICE FOR CAPPING OFF GLASS CYLINDERS.

1,339,200.

Specification of Letters Patent.

Patented May 4, 1920.

Application filed July 11, 1918. Serial No. 244,427.

To all whom it may concern:

Be it known that we, HARRY F. HITNER and TRAVIS E. OAKES, both citizens of the United States, residing, respectively, at 5 Creighton, in the county of Allegheny and State of Pennsylvania, and Mount Vernon, in the county of Knox and State of Ohio, have invented certain new and useful Improvements in Devices for Capping Off 10 Glass Cylinders, of which the following is a specification.

The invention relates to devices for severing glass cylinders transversely, by means of an electrically heated wire, such devices being known in the art as "capping off devices." It has for its principal objects, the provision of an improved and simplified device, (1) wherein the voltage required for the heating wire, as compared with the devices commonly used, is reduced, (2) wherein means are provided for a distribution of the current to correspond to the thickness of the glass where the cylinder is not uniform in thickness throughout its circumference, 25 (3) and which can be more rapidly and conveniently operated than the apparatus heretofore employed.

One embodiment of the invention is illustrated in the accompanying drawings where- 30 in Figure 1 is a transverse section through a cylinder with the capping off device in side elevation, Fig. 2 is a side elevation of the handle of the device on the side which carries the switch, Fig. 3 is a similar view 35 of the other side of the handle, Fig. 4 is a bottom plan view of the handle, Fig. 5 is an enlarged plan view of the wire clamp or clip, and Fig. 6 is an enlarged plan view 40 of the forked end of the transfer rod carried by the handle.

The handle 1 of the device carries a pair of terminals 2 and 3, (Fig. 2), the terminal 2 being connected to the contact plate 4 while the terminal 3 is connected to the 45 clamp 5. The forward end of the handle is provided with a metal housing 6 carrying a tension wheel 7, also of metal, such wheel being held yieldingly against rotation by a spiral spring (not shown). The housing 6 is provided with a spring 8 whose end 9 is opposite the plate 4 but out of contact therewith as indicated in Fig. 4. When this spring is pressed down by the thumb of the operator a connection is made between the

terminal 2 and the metal housing 6 and the 55 tension wheel carried thereby.

Secured to the tension wheel 7, and having several turns thereon, is the heating wire 10 of some high resistance metal such as is well known in the art. The other end of 60 this wire is free so that it may be passed around the cylinder to provide the necessary loop. The free end of the wire after passing around the cylinder is attached to the housing 6 in electrical contact therewith 65 so that the current from the terminal 2 passes around the cylinder in both directions. In order to complete the circuit the clamp 5 carried by the terminal 3 is provided, such clamp being adapted to be attached to the wire at some point opposite the handle 1 as indicated in Fig. 1. If the cylinder is of uniform thickness this clamp is ordinarily attached exactly opposite the handle, that is at 180° therefrom, but if the 70 cylinder is of unequal thickness the distance may be unevenly divided between the two portions of the loop, the shorter portion engaging that part of the cylinder which is 75 thickest. By this means the heating effect 80 of the wire upon the glass is made uniform regardless of any non-uniformity in the thickness of the wall of the cylinder.

The clamp is preferably made of the substantially U or V shape indicated in Fig. 5. 85 It consists of the member 11, preferably of spring material, such as tempered copper and a pair of jaws 12 and 13 secured to the opposite sides of the member 11 with their ends in engagement at 14 opposite the apex 90 of the V. These jaws conform to the contour of the V shaped member and may be made of copper or brass. Connection is made with the terminal 3 by having the ends of such terminal divide as indicated 95 at 15 and extend under the nuts of the bolts 17 which serve to secure the jaws of the clamp in position. The jaws are opened by pressing the ends of the V shaped member 100 toward each other, the wire then being gripped between the ends of the jaws when the pressure on the ends of the V shaped member is released. This clamp will securely hold the wire making good electrical contact therewith, and at the same 105 time it does not carry the wire out of engagement with the glass.

As a convenient means for passing the

- clamp from the handle side of the cylinder to the other side the transfer rod 18 is secured to the handle, such transfer rod being provided with a forked end 19 as indicated in Fig. 6.
- 5 The clamp 5 is placed in this fork by the operator on the handle side and when the handle is positioned as indicated in Fig. 1 the clamp is easily reached by the operator on the other side. In some cases this transfer rod may be utilized without the need of the second operator in which case the operator on the handle side reaches his free arm around the upper portion of the cylinder, at the same time extending the handle 15 around on the lower side of the cylinder.

The arrangement of the wire will be readily understood by reference to Figs. 3 and 4. The end of the wire which is attached to the handle passes through an opening in the metal pin 20. The wire then passes over the pin 21 and around the cylinder, its free end crossing the first portion of the wire opposite the pin 21 as indicated in Fig. 3. This end then passes around the third pin 22, around the edge of the housing 6 as indicated in Fig. 2, and beneath the spring clip 23. At this time the tension wheel 7 is so positioned that the wire is under tension, and this tension keeps the wire in proper engagement with the cylinder regardless of any contraction or expansion incident to temperature changes in the glass or wire. As will be seen by reference to Figs. 3 and 4, the pin 22 has its end cut back so as to provide a shoulder 24 in alignment with the opening 25 through the pin 20. It follows that when the wire is passed around the pin 22, and pushed up against the shoulder two portions of the wire contact with each other so that 40 there is no portion of the glass at this point which is not heated. This arrangement provides a continuous heated circle around the cylinder. Other forms of stops might be provided for bringing the two ends of the 45 wire into proper relative position.

After the apparatus has been adjusted as indicated in Fig. 1 the thumb of the operator is applied to the spring 8 causing it to engage the plate 4, thus causing it to complete the electrical circuit between the terminals 2 and 3. The heating of the wire heats the cylinder throughout its circumference at the line of contact to such an extent that the glass is cracked.

55 It will be seen that the apparatus as heretofore described and illustrated constitutes an effective and convenient means for accomplishing the electrical capping off or severing of cylinders. The voltage required is relatively lower than that heretofore required where the current was caused to pass completely around the cylinder from one terminal on the handle to the other terminal on such handle. Incidentally shocks to the 65 operators are thus minimized. The appa-

ratus also has the advantage heretofore referred to incident to the possibility of distributing the current uniformly to correspond to the thickness of the wall of the cylinder where the cylinder is not of uniform thickness throughout its circumference. Other advantages incident to the convenient handling of the apparatus will be apparent to those skilled in the art.

What we claim is:

1. In combination in a capping off device, a terminal, a loop of heating wire connected to the terminal, and a second terminal having a contact clamp adapted to be attached to the loop at any desired point opposite the 75 first terminal.

2. In combination in a capping off device, a terminal, a loop of heating wire connected to the terminal, a second terminal, and a contact clamp on said second terminal 85 adapted to grip the opposite sides of the heating loop wire at a point on the loop remote from the first terminal.

3. In combination in a capping off device for cylinders, a terminal, a heating wire 90 connected at one end to the terminal with the other end free and adapted to be passed around a cylinder forming a loop and attached to said terminal, and a second terminal adapted to be applied to the loop of wire 95 on the side of the cylinder opposite the first terminal.

4. In combination in a capping off device for cylinders, a terminal, a heating wire connected at one end to the terminal with the 100 other end free and adapted to be passed around a cylinder forming a loop and attached to said terminal, and provided with a contact clip for gripping the loop of wire on the side of the cylinder opposite the first 105 terminal.

5. In combination in a capping off device for cylinders, a terminal, a heating wire connected at one end to the terminal with the other end free and adapted to be passed 110 around a cylinder forming a loop and attached to said terminal, and provided with a spring contact clip adapted to grip the opposing sides of the heating wire loop at a point on the cylinder opposite the first 115 terminal.

6. In combination in a capping off device for cylinders, a handle, a terminal carried thereby, a loop of heating wire adapted to encircle a cylinder and connected to the terminal, an insulated terminal wire free at one end carried by the handle, and a contact clip carried by said free end of the terminal wire and adapted to be connected to the loop on the side of the cylinder opposite the 125 handle.

7. In combination in a capping off device for cylinders, a handle, a terminal carried thereby, a loop of heating wire adapted to encircle a cylinder and connected to the ter- 130

- 5 minal, an insulated terminal wire free at one end carried by the handle, and a contact clip carried by said free end of the terminal wire and adapted to be connected to the 5 loop on the side of the cylinder opposite the handle, the said loop having one end releasable from said terminal on the handle to facilitate its application around the cylinder.
- 10 8. In combination in a capping off device, a handle, a tension means on the handle, a heating wire secured at one end to the tension means, a guide member provided with a guide passage through which the wire extends, a guide member in proximity to the first guide member and provided with a stop in substantial alinement with said passage, and means for securing the free end of the wire to the handle.
- 15 9. In combination in a capping off device, a terminal provided with a loop of heating wire, and a second terminal provided with a clamp for attachment to said loop, said clamp comprising an approximately V shaped member of spring material, and a pair of jaws fixed to the opposite sides of said member and fitting the contour thereof with their ends lying in opposition at the point of said member.
- 20 10. In combination in a capping off device, a terminal provided with a loop of heating wire, and a second terminal provided with a
- 35 clamp for attachment to said loop, said clamp comprising an approximately V shaped member of spring material with the apex thereof rounded, and a pair of jaws fixed to the outer sides of said member and fitting the contour thereof with their ends lying in opposition close together and in contact with said apex so as to grip the relatively small heating wire.
- 40 11. In combination in a capping off device for cylinders, a handle, terminal carried thereby, a loop of heating wire adapted to encircle a cylinder and connected to the terminal, an insulated terminal wire connected to the handle at one end and carrying a wire engaging clamp at the other, and a transfer rod projecting forwardly from the handle and adapted to support the clamp and pass it from one side of the cylinder to the other.
- 45 12. In combination in a capping off device for cylinders, a handle, terminal carried thereby, a loop of heating wire adapted to encircle a cylinder and connected to the terminal, an insulated terminal wire connected to the handle at one end and carrying a wire engaging clamp at the other, and a curved transfer rod projecting downwardly and forwardly from the handle and adapted to support the clamp and pass it from one side of the cylinder to the other.

HARRY F. HITNER.
